INNER TUBE FOR PNEUMATIC TIRES

Miles C. McWherter, Derry, Pa.

Application November 13, 1935, Serial No. 49,595

1 Claim. (Cl. 152—13)

This invention relates to inner tubes for pneumatic tires and has for the primary object the provision of a device of this character which will retard the escape of air from the inner tube 5 when punctured or ruptured to prevent rapid deflation of the tire and accidents incidents thereto.

With these and other objects in view, this 10 invention consists in certain novel features of construction, combination and arrangement of parts to be hereinafter more fully described and claimed.

For a complete understanding of my invention, reference is to be had to the following description and accompanying drawing, in which 15

Figure 1 is a transverse sectional view illustrating an inner tube constructed in accordance with my invention.

Figure 2 is a transverse sectional view showing 20 the inner tube adapted to a pneumatic tire.

Figure 3 is a vertical sectional view showing the inner tube.

Referring in detail to the drawing, the numeral 1 indicates an outer elastic tubular wall 25 provided with an opening 2 to receive the usual inflating valve 3. Arranged in the wall 1 is a tubular elastic inner wall 4 joined to the outer wall, as illustrated at 5, so that the opening 2 extends therethrough permitting the inner end 30 of the inflating valve to be disposed inwardly of the inner wall 4. The inner wall 4 is slit circumferentially and arranged in overlapped relation, as shown at 6. The overlapped por-

tions of the inner wall at spaced intervals are joined, as shown at 7. The inner wall 4 is of an increased diameter over the diameter of the outer wall 1.

An inner tube of the character described when inflated by air pressure, said air pressure will equalize around the inner and outer faces of the inner wall so that when the outer wall 1 is punctured or ruptured, as shown in Figure 2, 10 the inner wall at this point moves away from the outer wall to prevent puncturing thereof so that when the air escapes through the puncture or blowout of the outer wall 1, the internal pressure against the inner face of the inner wall 15 4 will force the latter tightly over the rupture or puncture of the outer wall and partially seal the same so that the escape of air will be gradual or slow from the inner tube, consequently obviating rapid deflation of a tire equipped with 20 the inner tube.

Having described the invention, I claim:

An inner tube comprising an outer elastic tubular wall, an inner elastic tubular wall arranged in said outer wall and of a diameter 25 greater than the diameter of said outer wall, said inner wall being split circumferentially to form overlapped portions, said overlapped portions being joined to one another at spaced intervals, said inner and outer walls joined together at one point and provided with an opening therethrough, and an inflating valve mounted in said opening.

MILES C. MCWHERTER.
